UNITED STATES PATENT OFFICE.

WILLIAM GUTENKUNST, OF MILWAUKEE, WISCONSIN.

STANCHION.

Application filed January 11, 1926. Serial No. 80,540.

This invention relates to improvements in stanchions.

It is one of the objects of the present invention to provide a channel iron stanchion having a loosely mounted guide member controlling the opening and closing movement of the stanchion sides.

A further object of the invention is to provide a stanchion having simple and effective stop means for limiting the opening movement of the stanchion.

A further object of the invention is to provide a stanchion equipped with novel, accessible, and easily operated releasable latch means for retaining the stanchion in closed position.

A further object of the invention is to provide a stanchion which may be adjusted to vary its width in closed or latched position.

A further object of the invention is to provide a stanchion which is of very simple construction, is strong and durable, is relatively inexpensive to manufacture, and is well adapted for the purposes described.

With the above and other objects in view the invention consists of the improved stanchion and its parts and combinations as set forth in the claims, and all equivalents thereof.

In the accompanying drawing in which the same reference characters indicate the same parts in all of the views:

Fig. 1 is a front view of the improved stanchion;

Fig. 2 is a plan view thereof;

Fig. 3 is a sectional view taken on line 3-3 of Fig. 1 and on a larger scale;

Fig. 4 is a sectional view taken on line 4-4 of Fig. 1 and on a larger scale;

Fig. 5 is a fragmentary front view of the stanchion looking from the side opposite to that shown in Fig. 1 and showing the stanchion unlatched;

Fig. 6 is a detail view of the guide member;

Fig. 7 is a bottom view of the stanchion;

Fig. 8 is a sectional view taken on line 8-8 of Fig. 1 and on a larger scale;

Fig. 9 is a fragmentary view illustrating a slight modification of the invention; and

Fig. 10 is an enlarged sectional view of the bottom portion of the modified form of the invention.

Referring now more particularly to the drawings it will appear that the numerals

12 and 13 indicate the arms of the stanchion, both being formed of channel iron turned outwardly, and both being curved inwardly at their upper and lower end portions.

The upper end portions of both arms have bolted thereto shoe members 14 and 15, each arm and each shoe being formed with a plurality of openings to register in different positions whereby adjustments of the shoes with respect to the arms are attained. One of the shoe members as 15, carries a pivotal latch 16 to engage a lug 17 formed in the other of said shoe members, to releasably hold the stanchion arms in closed position. Each of said shoe members is formed with an upstanding ear through which bolts 18 and 19 extend transversely. Slidably mounted on said bolts, between the ears and washers 20, is an elongated slotted guide member 21, having flanged edges to form a track and shaped particularly as shown in Figs. 4 and 6. The slot of said guide member is divided medially by a portion 22 to form a stop. Thus, when the stanchion is opened or closed there is a sliding engagement between the bolts 18 and 19 and the guide member and outward movement is limited by the outer ends of the slots.

Secured to the ear portion of the shoe 14 is a link chain 23, by which means the stanchion is suspended in a stall.

The lower end portions of the arms are adjustably and hingedly connected together so as to permit opening and closing of the arms with respect to each other. To this end shoes 24 and 25 are bolted to the channels of the lower end portions of the arms and the ends of the shoes are forked, as shown in Fig. 7, and held together by a pivot bolt 26. To adjustably secure the shoes to the arms, the lower end portion of each arm is provided with a plurality of openings 27 for registration with any of the openings 28 of each shoe, the shoes and arms being held together by bolts 29 passed through the registering openings. By these means, therefore, in conjunction with the adjustments between the upper ends of the arms and the upper shoes, the width of the stanchion in closed position may be varied when required.

A chain 30 is held by the pivot bolt 26 and affords means for securing the lower end portion of the stanchion to a stall. Riveted to one of the stanchion arms, as 13, is a bi-

furcated member 31 which serves as a handle in operating the stanchion and also engages a post of the stall when the arm is moved to open position.

5 In Figs. 9 and 10 a slightly modified form of the invention is illustrated. As shown in Fig. 9 the channel of the arms 12' is turned inwardly to receive wooden strips 32 held in place by wood screws 33. The lower end 10 portions of the arms are also somewhat modified (see Fig. 10) and the shoes 24' are secured to the outer portions of the arms.

From the foregoing description it will be seen that the improved stanchion is of very 15 simple and novel construction, and is well adapted for the purposes set forth.

What I claim as my invention is:

1. A stanchion, comprising a pair of vertical arms hinged together at one end and 20 closing at the other end, an elongated guide member loosely carried by said arms, there being a slot and projection engagement between said guide member and the side portions of the closing ends of said arms, and 25 locking means for releasably holding said arms in closed position, the arms being movable in said guide member, and the guide member being movable on the arms.

2. A stanchion, comprising a pair of vertical arms hinged together at one end and 30 closing at the other end, shoe members adjustably carried by the upper end portions of said arms, projections extending laterally from said shoes, an elongated transversely 35 extending slotted guide member in engagement only with said projections, stanchion supporting means connected to one of the shoe members, and locking means carried by said shoes for holding said arms in closed 40 position.

3. A stanchion, comprising a pair of vertical arms hinged together at their lower ends and closing at their upper ends, shoe members adjustably carried by the upper end portions of said arms, pins extending laterally from said shoe members, an elongated slotted guide member loosely mounted thereon, said pins slidably engaging said slotted member exteriorly of said arms, and locking members carried by said shoe members for releasably holding the arms in closed position, the guide member being independently longitudinally movable on said pins. 45

4. A stanchion, comprising a pair of vertical channeled arms, shoe members adjustably carried by the upper end portions of said arms, pins extending laterally from said shoe members longitudinally movably mounted only thereon and freely slidable with or independently of the arms, an elongated slotted guide member, said pins slidably engaging said slotted member exteriorly of said arms, locking members carried by said shoe members for releasably holding the upper end portions of the arms together, and lower shoe members pivotally secured together and adjustably secured to the lower end portions of the arms. 55

5. A stanchion, comprising a pair of vertical arms hinged together at the lower ends and closing at the upper ends, lugs extending laterally from the upper end portions of said arms, a narrow bar formed with an elongated slot medially divided by a stop, one of said lugs engaging each portion of the slot, the plane of the bar being vertical, and locking means engaging said arms only in closed position. 70

In testimony whereof, I affix my signature.

WILLIAM GUTENKUNST.
